its end with oscillations to give a bearing to the wings without any lateral movement of the airplane and no reaction of the air is obtained on the longitudinal axis of the airplane. The invention is particularly intended for aircrafts having a lateral and longitudinal stability which is not due to the natural stability of the airplane.

UNITED STATES PATENT OFFICE

OTTO EDUARDO BEMBERG, OF PARIS, FRANCE

AUTOMATIC AERODYNAMIC STABILIZER FOR AIRPLANES

Application filed October 5, 1931, Serial No. 567,055, and in France August 26, 1931.

This invention has for its object a device, applicable to all existing airplanes, intended to automatically ensure the lateral and eventually longitudinal stability of airplanes and other machines for aerial navigation.

The principle of the invention consists in creating a vertical line independent of the oscillations of the airplane, and to take a bearing on members maintained in this vertical for automatically actuating the stability controls.

In other words, the invention consists in an apparatus in which no reaction is obtained by taking a bearing on the airplane, but solely on the air.

This apparatus consists in an auxiliary device connected to the airplane at a single point, either by a universal or Cardan joint, or by two links, two hooks, or a simple flexible bond, this device having planes or surfaces on which the air reacts during flight so as to lift it above the airplane, the plane defined by its longitudinal axis and the centre of the above joint being always vertical during flight.

The invention comprises a form of construction in which the above device is constituted by a series of planes intersecting on an axis suitably raised relatively to the horizontal, about which it loosely rotates, and by a rudder, placed behind, and also constituted by a group of planes which forces the group of intersecting planes to come in such a position that a reaction of the air results therefrom, thus producing a vertical upward thrust.

The actuation is effected by means of a vertical shaft rigid with the frame of the auxiliary device. A vertical auxiliary plane, loose about this shaft, can be provided for giving a greater efficiency to the balancing or wing flap control.

The invention is illustrated, but by way of example only, in the accompanying drawings, in which:

Fig. 1 is an elevation showing an airplane provided with the new device.

Fig. 2 is a corresponding plan view.

Fig. 3 is an elevation, on an enlarged scale, of the device forming the subject-matter of the invention.

involves of greater conception, related even to the present invention, and the present invention is not to be considered as limited to the specific embodiment shown, but is intended to cover all equivalents thereto.

Fig. 4 is a front view, the airplane being assumed stationary.

Fig. 5 is a front view corresponding to Fig. 4.

Figs. 6 and 7 illustrate modifications.

As shown in the drawings, between the wings of an airplane and at the upper part of the said wings is secured a support *a*, on which is bolted an angle iron *b* in the shape of a very open V, Fig. 5, one of the sides of which is perforated for securing the bolts in the support *a*, and the other end is integral with a Cardan joint *c*. The upper part of this Cardan joint has a jaw or yoke *c* which firmly embraces a spar *d*, made of wood, or constituted by an aluminium tube or in any other suitable manner, and raised to about 15° on the quarter of its length.

On the raised portion of this spar are secured at right angles, two uprights *e*, *e*¹ carrying a shaft *f*, about which can loosely rotate a group of convergent and intersecting planes *g*. For convenience, this group of intersecting planes will be hereinafter designated by the term "daisy" owing to its shape. These convergent planes can eventually be replaced by a dihedral *D*, Fig. 6, or by a cylinder *C*, Fig. 7, loosely mounted on their shaft *f*.

At the rear end of the spar *d* is mounted a rotary multiplane rudder *h*, loosely rotating about its shaft, the extension of which passes through the centre of the Cardan joint *c*.

Between the Cardan joint and the support *a*, a vertical shaft *i* is secured to the spar *d*; this vertical shaft *i* is arranged as near as possible in the vertical extension of the axis of the Cardan joint, about which a plane *j* can loosely rotate. The controls *o* of the balancing or wing flaps *k*, Fig. 2, are secured at *i* to this plane *j*. A support *n* serves to carry the spar *d* when at rest.

The operation is as follows:

When at rest, the daisy and its spar rest on one of the edges of the Cardan joint (Fig. 4), lying on the side after having pivoted about the longitudinal axis of the Cardan joint, the rudder resting on the support *n* arranged at a level lower than the Cardan joint, as illustrated in Fig. 3. In this position, the shaft *f* and the convergent planes will there-

fore have an incidence relatively to the horizontal.

If the airplane starts, as soon as the speed is sufficient, the entire device will tend to 5 pivot, that is to say, to plane itself askew in the wind. But, at this moment, the multi-plane rudder *h* will act and will hold the spar *d* in the axis of the airplane; the daisy, under the action of the wind, will rise vertically above the wings of the airplane, and 10 will maintain this position as long as the airplane flies.

The incidence of the main wings of the airplane and the incidence of the shaft *f* 15 will be so calculated that with a speed materially less than that necessary for causing the airplane to get off, the daisy must rise vertically. The convergent planes *g* being loosely mounted on their shaft, whatever may 20 be the wind striking against these planes, the uprights *e* will remain in a vertical position. The daisy will exert above the wings, whatever may 25 be the speed of the airplane, a vertical pull and will hold the shaft *i* in a vertical position.

If the airplane tends to incline laterally, the support *a* rigid with the airplane, will take the same inclination. But, owing to the Cardan joint *c*, the vertical pull of the daisy 30 will hold the device, and the uprights *e* and shaft *i* will remain in the vertical plane. Consequently, the plane *j* will exert a pull on one of the controls *o* and will release the opposite control, that is to say will cause the 35 side balancing flaps to act, so as to stabilize the airplane in the lateral direction.

The shaft *i*, being placed just below the Cardan joint, the spar *d* can oscillate about the axis of the Cardan joint and even pitch, 40 without materially modifying the positions of the controls relatively to the plane *j*.

In order to diminish as much as possible the tractive stress on the plane *j*, the main balancing or wing flaps instead of being constructed as usual, that is to say with a side hinge, will be constituted by a simple plane 45 with central axis so as to form compensated planes; a lever arm will act on each balancing flap which will lower or rise as a simple 50 shutter.

Concerning the controls themselves, they can be made in any suitable manner.

The above arrangements are given by way of example only, all the details of construction, the forms, dimensions and materials used can be modified according to circumstances, without departing thereby from the principle of the invention.

I claim:

60 1. An aerodynamic device adapted to automatically ensure the stability of airplanes and other apparatus for aerial navigation, comprising a wind vane formed by a group of intersecting planes freely rotating on a 65 shaft, a rudder integral with the said group of planes the group of which freely rotates

of planes, a swivel connection with the airplane, and means for using the movements of above system for acting on the controls.

2. An aerodynamic device adapted to automatically ensure the stability of airplanes 70 and other apparatus for aerial navigation, comprising a wind vane formed by a group of intersecting planes freely rotating on a shaft, a rudder integral with the said group of planes and also formed by intersecting 75 planes the group of which freely rotates about the shaft, a swivel connection with the airplane, and means for using the movements of above system for acting on the controls.

3. An aerodynamic device adapted to automatically ensure the stability of airplanes 80 and other apparatus for aerial navigation,

comprising a wind vane formed by a group of intersecting planes freely rotating on a shaft, a rudder integral with the said group of planes and also formed by intersecting 85 planes the group of which freely rotates on the shaft and the shaft of which forms an angle with that of the wind vane, a swivel connection with the airplane, and means for using the movements of above system for acting on the controls.

4. An aerodynamic device adapted to automatically ensure the stability of airplanes 90 and other apparatus for aerial navigation,

comprising a wind vane formed by a group of intersecting planes freely rotating on a shaft, a rudder integral with the said group of planes, and also formed by intersecting 95 planes the group of which freely rotates on the shaft and the shaft of which forms an angle with that of the wind vane and passes through the center of the joint, a swivel connection 100 with the airplane, and means for using the movements of above system for acting on the controls.

The foregoing specification of my: "Automatic aerodynamic stabilizer for airplanes" signed by me this 18th day of September 110 1931.

OTTO EDUARDO BEMBERG.
